UNITED STATES PATENT OFFICE.

CASSIUS M. RICHMOND, OF NEW YORK, N. Y., ASSIGNOR TO THE INTERNATIONAL TOOTH CROWN COMPANY, OF NEW YORK.

ARTIFICIAL-TOOTH CROWN.

SPECIFICATION forming part of Letters Patent No. 392,226, dated November 6, 1888.

Application filed October 31, 1887. Serial No. 253,851. (No model.)

To all whom it may concern:

Be it known that I, CASSIUS M. RICHMOND, of the city, county, and State of New York, have invented a new and useful Improvement 5 in Artificial Porcelains, of which the following is a full, true, and exact description, reference being had to the accompanying drawing.

In the manufacture of artificial dentures 10 great difficulty has been experienced from the detaching or breaking away of the artificial porcelains from the supporting gold in the process of mastication. The general method of making such porcelains has been to bake 15 into the back of the tooth a pin or pins practically parallel with the biting-surface of the tooth, or at right angles to its exterior face or crown. Under those circumstances, especially for molar teeth, it is plain that when such 20 teeth are attached by the supporting-pins to a backing of gold a very powerful leverage is exerted, tending to split off the tooth from the backing of gold. In order to prevent this destruction, various methods have been em- 25 ployed, among others a method for making the masticating-surface of the tooth of gold, as is exhibited in the patent to A. S. Richmond of May 22, 1883. In structures of that character, as is apparent, a large amount of 30 gold is necessary in order to secure a proper masticating-surface and sufficient strength in the structure. Moreover, when the masticating-surface of the tooth is made of gold the gold being carried to the face of the tooth 35 is more visible than when such gold does not exist beneath the tooth.

By my improved porcelain I am enabled to dispense with gold beneath the tooth, and at the same time make a denture which is equally 40 strong or stronger than the previous known dentures, and likewise to effect a large saving in the supporting gold.

My artificial porcelain is applicable to many forms of artificial denture, but is especially 45 useful in that part of the dental art applicable to the construction of bridge-work, where artificial porcelains are carried between the supporting ends of the bridge.

My invention consists in an artificial dent-

ure constructed substantially as hereinafter 5c set forth.

A structure embodying my invention is shown in the accompanying sectional drawing, in which A represents the porcelain face or artificial-tooth crown; B, the backing of the 55 gold, and C the supporting-pin.

The invention is illustrated as applied to a molar tooth. The porcelain itself, as will be observed, is much more massive than those usually employed, and its masticating-surface 60 consists of porcelain and not of gold, though it is apparent that the benefits of my invention in a less degree might be obtained even though the masticating-surface were of gold. The pin C is baked into the tooth in the usual 65 way in the process of manufacture, and preferably consists of iridium wire, about No. 16 in size. It is apparent, likewise, that more than one pin could be employed, if desired, though in practice I find one sufficient. The back- 70 ing B is applied to the back and side of the tooth, as shown, but is apparently much less in mass than has been customarily used in supporting this class of denture, the strength 75 of the porcelain in combination with the pecu- liar arrangement of the pin, serving to supply the necessary strength, which was formerly se- cured only by an increase in the mass of sup- porting gold. The relation of the pin in the 80 gold prevents both the upward and the lateral movement of the porcelain from the gold, as is apparent, whereas when the pin projects horizontally into the tooth it cannot prevent the lateral movement of the tooth excepting by the strength of the attachment of the pin 85 within the porcelain, whereas in the structure shown the pin serves as a support independ- ent of the attachment between the pin and the porcelain. The backing is applied in the well- 90 known way by soldering upon the projecting end of the pin, which should preferably prac- tically project to the inner surface of the back- 95 ing to insure the greatest strength.

In this specification I have called the lower part of the gold backing shown at B' the "lin- 95 gual surface" of the denture, and the upper part, B, the "palatine surface." In the pre- vious art the pins were connected with the

lower part of the backing B', and not with the upper angular surface, B. It is obvious that, though I have described the angle of the pin as about forty-five degrees, angles more or less approaching to this would be useful.

What I claim as my invention, and desire to secure by Letters Patent, is

An artificial denture which consists of a porcelain facing and a metallic backing consisting of an angular plate covering the lingual and palatine faces of the tooth, and a pin baked into the tooth and extending nearly to

the front thereof at an angle practically of forty-five degrees to its vertical axis and united with the metallic backing, thereby firmly connecting the parts, substantially as and for the purpose described.

In testimony whereof I have signed my name to this specification in the presence of two subscribing witnesses.

CASSIUS M. RICHMOND.
